(57) **CLAIM**

The ornamental design for a transport tool, as shown and described.

DESCRIPTION

FIG. 1 is a perspective view of a transport tool, showing my new design;

FIG. 2 is a perspective view thereof;

FIG. 3 is a top plan view of FIG. 2;

FIG. 4 is a bottom plan view of FIG. 2;

FIG. 5 is a left-side elevational view of FIG. 2, the right-side elevational view being a mirror image thereof;

FIG. 6 is a front elevational view of FIG. 2; and,

FIG. 7 is a rear elevational view of FIG. 2.

The broken lines showing a person transporting a load in FIG. 1 depict environmental matter and form no part of the claimed design. The remaining broken lines represent portions of the transport tool that form no part of the claimed design.

The disclaimed lettering on the figures represents the trademark SLIDEZALL, US Reg. 90680835, owned by the Applicant.
